UNITED STATES PATENT OFFICE.

MILLARD F. ELLIS, OF ATCHISON, KANSAS, ASSIGNOR OF ONE-HALF TO A. F. MARTIN, OF SAME PLACE.

BRICK FOR VENEERING FRAME HOUSES AND OTHER WOODEN BUILDINGS.

SPECIFICATION forming part of Letters Patent No. 313,930, dated March 17, 1885.

Application filed April 21, 1884. (No model.)

To all whom it may concern:

Be it known that I, MILLARD F. ELLIS, a citizen of the United States, residing at Atchison, in the county of Atchison and State 5 of Kansas, have invented certain new and useful improvements in bricks for veneering frame houses or other wooden buildings, and in the mode of securing the veneering brick wall to the frame of the house or building, of 10 which the following is a specification.

The object of my invention is to secure the veneering wall of brick to the frame of the house or building in such a manner as to allow the said veneering wall to finally settle 15 without cracking or becoming detached from the frame. I claim that by its adoption a frame building can be veneered with brick and the veneering wall can settle as much as veneering walls usually settle without danger 20 of cracking the said wall and without the possibility of its becoming detached from the frame of the building.

Heretofore the method of attaching and securing veneering walls of brick to frame buildings has been by spikes driven into the studding at the top of a certain number of courses of brick, and the next course of bricks laid upon said spikes, and thus they have been built into the wall solid, and the result has 30 been that when the wall settles, as all brick walls will, either the wall cracks or the spikes break, and thus the wall becomes wholly detached from the frame.

My object is attained by the peculiar shape 35 of the veneering bricks and the method of fastening, which are illustrated by the accompanying drawings and explained as follows:

Figure 1 represents a cross-section of the wall made with these bricks and showing them 40 in position. Fig. 2 represents a perspective view of a portion of the exterior of a building veneered with brick according to this invention. Fig. 3 represents a view of the upper surface of the brick outside of the wall. Fig.

4 represents a perspective view of the brick 45 out of the wall, being the same length and thickness as ordinary brick.

a a are bricks of this invention laid in wall. They are made by the same process and from the same material as the ordinary building, 50 brick, and differ from the ordinary bricks only in size and shape.

b b are ordinary building-brick used in connection with bricks of this invention.

c c are the studding of the frame of the 55 building.

d d are small cleats, of wood, seven-eighths of an inch square, nailed or spiked to outer edge of studding, and over or around which the slot in the brick *f f* in Figs. 3 and 4 works. 60

e e are the nails or spikes by which the cleat *d* is fastened to the studding *c*.

f f in Figs. 3 and 4 represents a slot in the brick to receive the cleat *d*, so that when the brick is laid in the wall according to this invention the cleat *d* is received into the slot *f*, and thus the brick is free to move up or down without being displaced in the wall, and at the same time the slot *f*, working around the cleat *d*, effectually prevents the wall from becoming detached from the frame. 70

Having thus described my invention, what I desire to claim and secure by Letters Patent is—

1. The peculiar shape of the brick *a a* for 75 veneering purposes, the same having a slot, *f*, substantially as described.

2. The method of securing said veneering bricks to the studding or frame of a house or building by means of wooden cleats *d d*, nailed 80 to said frame, over which the slots *f f* of said veneering bricks fit, and which hold the wall to the frame of the wooden building, substantially as and for the purpose set forth.

M. F. ELLIS.
